UNITED STATES PATENT OFFICE.

WILLIAM BODGE, OF NUTLEY, NEW JERSEY, AND JOHN B. WEISMILLER, OF NEW YORK, N. Y.

COUNTING DEVICE.

1,208,083.

Specification of Letters Patent. Patented Dec. 12, 1916.

Application filed May 4, 1916. Serial No. 95,383.

To all whom it may concern:

Be it known that we, WILLIAM BODGE and JOHN B. WEISMILLER, citizens of the United States, and residents, respectively, of Nutley, county of Essex, State of New Jersey, and New York, county of Bronx, State of New York, have invented certain new and useful Improvements in Counting Devices, of which the following is a specification.

10 The invention relates to improvements in counting devices arranged for attachment to machines for making or operating upon envelops or other articles, whereby the work may be automatically counted during delivery by laterally displacing from its normal path of travel one of said articles from each predetermined number thereof, thus dividing the delivery into equal groups or series; the device being particularly adapted to high 15 speed machines in which the articles are delivered in spaced relation to each other at a comparatively rapid rate of speed.

20 The object of the invention is to provide means for effecting such lateral displacement instantaneously to avoid disturbing the work on opposite sides thereof.

25 The invention further includes the general arrangement and the detail construction of the several parts thereof, as hereinafter set forth.

30 In describing the invention in detail, reference is had to the accompanying drawings, forming a part of this specification, and wherein like characters of reference are used 35 to designate corresponding parts throughout the several views, and in which:

40 Figure 1 is a diagrammatical plan view of an ordinary delivery of an envelop machine, shown in connection with the improved counting device; Fig. 2 is a side elevation of the same; Fig. 3 is an enlarged side view showing the detail construction of the counter, and Fig. 4 is an end view of the latter.

45 In the drawings numeral 1 designates a plate or bracket for supporting the operating parts of the counter, and 2, an arm formed on the bracket and adapted to be secured in any approved manner to the 50 main machine on which the counter is to be applied. Fixed to the bracket is a stud 3, on which are loosely mounted the jointly connected ratchet-wheel 4 and trip-cam 5. Loosely mounted upon the stud 3 between

the bracket and ratchet-wheel is a rock-arm 55 6 carrying a pawl 7, arranged to engage the ratchet-wheel and effect a step-by-step rotation thereof, the free end of the rock-arm being pivotally jointed to a connection-rod 8, arranged to receive reciprocating movements from a convenient motive element of the main machine and effect an advance step movement of the ratchet-wheel at the delivery of each envelop. The trip-cam 5 is provided with an abrupt drop, or trip member 60 9, and forms therewith an eccentric perimeter or working face 10, disposed to engage the upper end of the oscillatory actuating member or lever 11, the latter being pivotally supported intermediate its ends by a shouldered stud formed on the bracket 1, the lever being held in place thereon by the terminal screw 12 and washer 13. At its lower end the lever is pivotally connected with a trip-rod 14, which is provided with a drive-tooth 75 15, adapted to engage a catch 16, fixed to the thrust-bar 17, the drive-rod being normally held in engagement with the catch by the spring 18, connected at its upper end to the bracket 1 by the pin 19. 80

85 The thrust-bar 17 is pivotally supported at its upper end on a shouldered stud 20, formed on the bracket 1, and is held in place thereon by the terminal screw and washer shown. The thrust-bar 17 and trip-rod 14 are laterally guided for movement by the projecting right-angle block 21, formed on the bracket 1, the block being provided with 90 guide recesses inclosed by the right-angle cover-plate 22. As herein shown, the thrust-bar is angular in form and is provided with a projecting thrust member 23, adapted to engage the work to be operated upon. A resilient spring 24 is connected at one end to the thrust-bar and at its opposite end to 95 the pin 24^a, fixed to the bracket 1. The spring 24 normally holds the thrust-bar in the retracted position shown in full lines, and for projecting the bar into the position indicated in dotted lines, against the action 100 of this spring, a second spring 25 of increased tension is employed, the latter being connected at one end to the upper end of the actuating lever 11, while the opposite end of the spring is secured to a pin 26, fixed 105 in the bracket 1.

In the operative rotation of the trip-cam 5, the trip-member 9 thereof releases the ac-

tuating lever 11, permitting an instantaneous movement of the latter by the action of the recoil spring connected thereto, which movement causes a correspondingly rapid 5 forward or projecting motion both in the trip-rod 14 and in the thrust-bar 17. The forward movement of the trip-rod is limited by the engagement of the upper end of the actuating lever 11 with the low portion of 10 the trip-cam 5, as indicated in dotted lines, while the forward movement of the thrust-bar 17 is limited by the engagement of the beveled portion 27 of the trip-rod 14 with the stop 28, causing the trip-rod to be depressed and released or tripped from its connection with the catch 16, whereupon the thrust-bar will be instantaneously retracted by the action of the spring 24. As the step-by-step rotation of the trip-cam 5 continues 15 in its cycle of counting action, the engagement thereof with the lever 11 causes a gradual return movement of the trip-rod 14 to its former retracted tripping position. To provide against an accidental backward 20 movement of the trip-cam and ratchet-wheel, an ordinary stop pawl 29 is employed, and to provide against accidental forward movement, a tension device is used, consisting of a collar 30, adjustable longitudinally on 25 the end of the fixed stud 3, the collar being yieldingly connected to the friction washer 31 by the spring 31^a. The several parts of the tension device are connected together 30 against rotation and the washer 31 is yieldingly held in frictional engagement with 35 the side face of the trip-cam 5 by means of the set-screw 30^a.

In the application of the counting device 40 to an envelop machine provided with the common form of delivery mechanism shown in Figs. 1 and 2, wherein numerals 32 designate a portion of a pair of rotatable delivery wheels, partially encircled by the belts 33, which latter pass around pulleys 34, fixed 45 to a rotatable conveyer-shaft 35, the latter being provided with conveyer belts 36, leading to any desired point. Above the conveyer belts 36 are disposed a portion of a pair of endless cords 37, extending around 50 the idler pulleys 38, the latter mounted on arms 39, whereby the position of the cords with respect to the belts may be adjusted for guiding and controlling the upper edges 55 of envelops of variable widths.

55 From between the delivery wheels 32 and the belts 33, the envelops are delivered in spaced relation with each other upon the conveyer belts 36 and in which delivery the upper edges thereof are positioned by the deflector-wheels 40, loosely mounted for adjustment on the arms 41.

As indicated in the drawings, the counting device with respect to its thrust member 23 is positioned adjacent the path of the 60 envelops as delivered from the machine, and

the support therefor may be connected in any 65 approved manner to a fixed part of the main machine. Also for actuating the counter, any convenient movable member of the 70 machine may be employed whereby oscillatory movements may be had corresponding with the delivery of the envelops. As diagrammatically shown in Fig. 1, these movements 75 may be effected by a cam 42, fixed to the end of the rotatable conveyer-shaft 35, the cam being provided with the required number of 80 actuating surfaces for engaging the oscillatory arm 43, pivotally connected to the fixed support 44. The movements of the arm 85 43 are transmitted through the above-mentioned connecting-rod 8 to the rock-arm 6 of the counter.

As thus connected for operation it will be 90 obvious that the thrust-bar 17 of the counter will be instantaneously projected and retracted at each revolution of the ratchet-wheel 4, which, as herein shown contains twenty-five teeth, corresponding with the 95 number of envelops delivered per revolution. In the position shown in Fig. 3, the cam 5 of the counter is about to trip the lever 11 for effecting the projection of the thrust-bar 17 and laterally displacing from its normal path of travel an envelop carried on the 100 delivery-belts 36, the former action of the thrust-bar being indicated by the displaced envelop 45, the advanced position of which shows the result of its operation in dividing the delivered work into groups or series containing an equal number of parts.

It will be obvious that the counting device with respect to its divisional action upon the work may be varied for any required number, by replacing the ratchet-wheel and trip-cam with corresponding parts having the 105 desired number of teeth and trip members respectively, and it also will be evident that the instantaneous action of the thrust-bar upon the articles to be displaced will permit of a relatively rapid rate of delivery without 110 accidental displacement of the adjacent work.

What we claim as our invention and desire to secure by Letters Patent, is:

1. In a counting device, a thrust-bar, resilient means normally retracting said thrust-bar, resilient means normally adapted to project said thrust-bar in opposition to said retracting means, means controlling the 115 action of said resilient projecting means, means for periodically tripping said controlling means and projecting said thrust-bar, and means for tripping said projecting means to permit the retraction of said thrust-bar.

2. In a counting device, a thrust-bar, resilient means normally retracting said thrust-bar, a trip-rod engaging said thrust-bar, resilient means engaging said trip-rod and normally adapted to project said thrust- 120 125 130

bar in opposition to said retracting means, a trip-cam controlling the action of said trip-rod, means for tripping said trip-cam to permit the action of said trip-rod, and 5 means for tripping said trip-rod to permit the retraction of said thrust-bar.

3. The combination with a conveyer arranged for delivering articles in spaced relation with each other, of a counting device 10 therefore comprising a thrust-bar, resilient means for retracting said thrust-bar, resilient means for projecting said thrust-bar in opposition to said retracting means for engaging and displacing one of the articles in 15 each predetermined number thereof during delivery, and means for tripping said projecting means to permit the retraction of said thrust-bar.

4. The combination with a conveyer arranged for delivering articles in spaced relation with each other, of a counting device therefore comprising a thrust-bar, resilient means for retracting said thrust-bar, resilient means for projecting said thrust-bar in 25 opposition to said retracting means for engaging and displacing one of the articles in each predetermined number thereof during delivery, a trip-cam controlling the action of said projecting means, means for tripping said trip-cam at the delivery of each 30 predetermined number of articles, and means for tripping said projecting means to permit the retraction of said thrust-bar.

5. In a counting device, the combination 35 with a support, of a thrust-bar mounted on said support, resilient means normally retracting said thrust-bar, a trip-rod engaging said thrust-bar, resilient means carried by said support and acting through said 40 trip-rod to project said thrust-bar in opposition to said resilient retracting means, and means for tripping said trip-rod to permit the retraction of said thrust-bar.

6. In a counting device, the combination 45 with a support, of a thrust-bar mounted on said support, resilient means normally retracting said thrust-bar, a trip-cam rotatably mounted on said support, an actuating member engaging said trip-cam, a trip-rod 50 connected to said actuating member and engaging said thrust-bar, resilient means connected to said actuating member and effecting said trip-cam engagement, means for rotating said trip-cam for the release of said 55 actuating member whereby said thrust-bar is projected by the recoil of said resilient means thereof, and means for tripping said trip-rod to permit the retraction of said thrust-bar.

60 7. In a device for counting articles in movement, the combination with a support adjacent the path thereof, of a thrust-bar mounted on said support, resilient means normally retracting said thrust-bar, a trip- 65 cam rotatably mounted on said support, an

actuating member engaging said trip-cam, a trip-rod connected to said actuating member and engaging said thrust-bar, resilient means connected to said actuating member and effecting said trip-cam engagement, 70 means for rotating said trip-cam for the release of said actuating member whereby the said thrust-bar is projected by the recoil of said resilient means for engagement with the articles in movement, and means for 75 tripping said trip-rod to permit the retraction of said thrust-bar.

8. In a counting device, the combination with a thrust-bar, of resilient means normally retracting said thrust-bar, a trip-rod 80 detachably connected to said thrust-bar, resilient means operating through said trip-rod to project said thrust-bar in opposition to said resilient retracting means, and means for tripping said trip-rod.

9. In a counting device, the combination with a thrust-bar, of resilient means normally retracting said thrust-bar, a trip-rod detachably connected to said thrust-bar, an actuating member connecting said trip-rod, 90 resilient means engaging said actuating member and operating through said trip-rod to project said thrust-bar in opposition to said retracting means, and means for tripping said trip-rod.

10. In a counting device, the combination with a thrust-bar, of resilient means normally retracting said thrust-bar, a trip-rod detachably connected to said thrust-bar, an actuating member connecting said trip-rod, 100 resilient means engaging said actuating member and operating through said trip-rod to project said thrust-bar in opposition to said retracting means, a trip-cam operatively engaging said actuating member in opposition to the tension of said resilient projecting means, means for rotating said trip-cam to trip said actuating member for the operation of said resilient projecting means, and means for tripping said trip-rod. 105

11. In a counting device, the combination with a thrust-bar, of resilient means normally retracting said thrust-bar, resilient means detachably connected to said thrust-bar and normally projecting the same in opposition to said retracting means, a trip-cam adapted to effect connection between said thrust-bar and resilient projecting means, tripping means on said trip-cam permitting the operation of said projecting 115 means, and means for detaching the connection between said thrust-bar and projecting means.

12. In a device for counting articles in movement, the combination with a thrust-bar adapted to periodically displace one of the articles, of resilient means normally retracting said thrust-bar, resilient means detachably connected to said thrust-bar and normally projecting the same in opposition 125 130

to said retracting means, a trip-cam adapted to effect connection between said thrust-bar and resilient projecting means, means for effecting a step by step movement of the cam corresponding with the successive delivery of the articles, tripping means on said cam permitting the operation of said projecting means, and means for detaching the

connection between said thrust-bar and projecting means.

Signed at New York, in the county of New York and State of New York, this third day of May, A. D. 1916.
